(57) **CLAIM**

The ornamental design for portable X-ray machine as shown and described.

DESCRIPTION

- 1.1** : Perspective
1.2 : Perspective
1.3 : Front
1.4 : Back
1.5 : Left
1.6 : Right
1.7 : Top
1.8 : Bottom

1. The present design is made of metal and synthetic resin.
2. The present design aims to improve prevention of functional defects caused by damage to exposed cables on existing products. By applying a slip ring to the connection point, and removing the cable, the present design allows for smooth adjustment of the X-ray imaging area and direction.

1 Claim, 8 Drawing Sheets
